Whitman, Mass. 02382

Filed May 8, 1968, Ser. No. 11,843

Term of patent 14 years

Int. Cl. D19—08; D20—03

U.S. Cl. D96—12

FIG. 1 is a perspective view of a combined bulletin board and weather station, showing one face of my new design, the opposite face being a duplicate thereof,

FIG. 2 is an end elevational view thereof, and

FIG. 3 is a top plan view thereof.

The dominant features of my design reside in the portions shown in full lines.

I claim:

The ornamental design for a combined bulletin board and weather station, substantially as shown and described.
